Primary Examiner—Susan J. Lucas

[57] CLAIM

The ornamental design for a safety light for industrial areas, as shown and described.

DESCRIPTION

FIG. 1 is a perspective view of a safety light for industrial areas showing my new design

FIG. 2 is a cross-sectional view thereof as taken along line 2—2 of FIG. 1 on an enlarged scale

FIG. 3 is a cross-sectional view showing the edge of the front lens mounted to the housing on a greatly enlarged scale

FIG. 4 is a front elevational view thereof on a reduced scale

FIG. 5 is a right side elevational view thereof on a reduced scale, the left side being a mirror image

FIG. 6 is a top plan view thereof on a reduced scale

FIG. 7 is a bottom plan view thereof on a reduced scale

FIG. 1

FIG. 3

FIG. 2

FIG. 6

FIG. 4

FIG. 5

FIG. 7
